GLASS SYRINGE PACKAGING CARTON

Samuel Kolodny, Rutherford, N. J., assignor to
East Rutherford Syringes, Inc., East Rutherford, N. J., a corporation of New Jersey

Application April 12, 1950, Serial No. 155,431

2 Claims. (Cl. 206—63.2)

1

This invention relates to cartons for packaging and shipping fragile articles and, more particularly, to an improved carton for packaging a glass hypodermic syringe and arranged to protect the syringe and its constituent elements from breakage.

Such syringes are generally packed in a tray, of cardboard or the like, having a base, and side walls, the carton including a corresponding cover arranged to fit over the tray and close the same. These glass syringes require special protective arrangements to prevent accidental jarring and movement of the constituent parts. The syringes include a glass barrel slidably receiving a closely fitting glass plunger. One end of the barrel is open, to receive the plunger, and the other end terminates in a nozzle or the like to accommodate a hypodermic needle. The open end of the barrel usually has an annular flange, as does the projecting end of the plunger whereby the syringe may be gripped and operated with one hand. During shipment, unless special preventive means are provided, the glass plunger may strike the bottom of the barrel and result in breakage.

Various arrangements have been proposed for protecting the syringe during shipment, and include supporting disks engaging the barrel and cushioning disks inserted within the barrel to prevent the plunger striking the barrel bottom. Cotton or similar material has been packed around the syringe to prevent movement in the carton. All of these arrangements have been inconvenient, unsatisfactory, and expensive insofar as packaging is concerned.

It has been proposed to provide a special cardboard insert within the tray for engaging the syringe parts and preventing movement of the syringe relative to the carton and movement of the barrel relative to the plunger. This insert comprises an elongated cardboard strip folded about longitudinally folded lines and provided with a rather complicated series of cut-outs to receive the barrel and plunger flanges and provide space for grasping the syringe for insertion and removal. While it is a step forward in the art, the prior art insert has been unsatisfactory from the protective standpoint and has been rather expensive to form.

The present invention is accordingly directed to an improved insert, in which an elongated strip of cardboard or the like is folded about transverse folded lines to provide panels engaged with the tray base and a panel held in spaced parallel relation to the base. The first-mentioned panel forms a cushioning and reinforcing layer on the tray base. The second mentioned panel, and a

2

short wall supporting one end thereof, are formed with a cut-out receiving the outer ends of the barrel and plunger. This cut-out has lateral extensions receiving the mentioned flanges, and the longitudinal spacing of the extensions is greater than the spacing of the flanges when the plunger is engaged with the inner end of the barrel. Thereby, the plunger is held against striking the barrel bottom.

10 The insert further includes a pair of upwardly extending panels formed with matching recesses to engageably receive the inner end of the barrel. These recesses extend from the upper edges of such panels to points short of the lower edges thereto, in such manner that the barrel is supported in spaced parallel relation to the tray bottom or base. The throats of the recesses are of less width than the diameter of the barrel, so that the latter must be pressed into the recesses and is releasably locked therein against outward movement. Other portions of the strip from which the insert is formed act to properly space the first panel and the upwardly extending panels with reference to the end walls of the tray.

15 For a more thorough understanding of the principles of the invention, reference is made to the following description of a typical embodiment thereto as illustrated in the accompanying drawing. In the drawing:

20 Fig. 1 is a top plan view of the invention carton with the cover removed, illustrating, in broken lines, how a syringe is supported by the insert or filler therein.

25 Fig. 2 is a longitudinal sectional view on the line 2—2 of Fig. 1.

30 Figs. 3 and 4 are transverse sectional views on the correspondingly numbered lines of Fig. 2.

35 Fig. 5 is a plan view of the filler or insert blank before folding.

40 Referring to Fig. 1, the invention carton is arranged to protectively support a hypodermic syringe 10, of glass or similar material, comprising a barrel 11, terminating in a nozzle 12, and a plunger 13. Nozzle 12 is arranged to be operatively connected to the usual hypodermic needle in a known manner. Plunger 13 has a close sliding fit within barrel 11, and has a flange or head 14 at its outer end. Barrel 11 likewise has a flange 16 at its outer end. Flanges 14 and 16 provide a ready means for securing an operating grip on syringe 10, which is usually operated by one hand.

45 The carton 20 comprises an elongated rectangular tray having a base 21, ends 22 and sides 23, and is arranged to have a similarly shaped cover

(not shown) fit thereto. The length of tray 20 is somewhat greater than that of syringe 10.

In accordance with the invention, tray 20 contains an insert or filler of heavy cardboard or similar material designed to protect syringe 10 from breakage due to jarring of the carton or due to sliding of plunger 13 in barrel 11 so that the plunger inner end contacts the barrel inner end. Such contact results in fracture of the barrel or plunger or both.

Referring to Fig. 5, insert 30 is formed from an elongated rectangular strip 31 of flat material, preferably heavy cardboard. Strip 31 is folded along transverse fold lines 32 through 38 to provide sections 31a through 31h. Sections 31a and 31c are equal in length and arranged parallel to tray bottom 21 (Fig. 2), being interconnected at one end of the tray by a vertical wall formed by narrow section 31b. Section 31a, as best seen in Fig. 2, lies against tray bottom or base 21, whereas section 31c is in spaced relation to the tray bottom, being supported at its innermost end by the vertical wall formed by narrow section 31d.

The next section, 31e, likewise lies against tray bottom 21, and it will be noted that section 31a forms a limit stop for movement of section 31e to the left (Fig. 2). Sections 31f and 31g are folded about line 37 to form an inverted V, which is held in properly supported position by section 31h, lying against tray bottom 21 and abutting right end wall 22, and section 31a, abutting left end wall 22 and limiting leftward movement of section 31e.

Before strip 31 is folded as described, it is provided with cut-outs to receive syringe 10 and hold the same against movement within carton 20. A cut-out 40 in section 31c is shaped to receive plunger 13 and the inner end of barrel 11, having lateral extensions 41, 41 receiving flange 14 and lateral extensions 42, 42 receiving flange 16. The longitudinal spacing of extensions 41 from extensions 42 is greater than the spacing of flanges 14 and 16 when plunger 13 is fully pushed into barrel 11. Consequently, when the flanges are engaged in their respective cut-out extensions, the inner end of plunger 13 is maintained in spaced relation to the bottom of barrel 11, thus preventing accidental contact of these elements.

Cut-out 40 is continued into a cut-out 43 extending the full depth of section 31d, so that the outer end of syringe 10 rests on folded under extension 31a. This latter forms a reinforcing and cushioning layer on tray bottom 21 to protect the syringe against shock.

Identical and interconnected cut-outs 45, 46 are formed in sections 31f and 31g, respectively, having arc shaped outer ends conforming to the surface of barrel 11. The inner, connected ends of the cut-out have a lateral dimension less than the outer diameter of barrel 11, so that the cut-outs 45, 46 look, in plan, somewhat like a dumb-bell.

When sections 31f and 31g are folded about line 37 to form the inverted V, a supporting recess is formed which has an entrance throat of less width than the outer diameter of barrel 11. Consequently, some slight pressure must be used to force the outer end of the barrel into the recess, and the inwardly projecting lips 47, 47 retain the barrel against accidental movement out of the recesses. Cut-outs 45, 46 do not extend the full depth of sections 31f, 31g, so that barrel 11 is supported in spaced parallel relation to tray bottom 21.

The syringe 10 may be readily engaged in the insert 30, as shown in Figs. 1 and 2, and the cut-outs are so related to the end walls 22 of tray 20 so that the outer end of plunger 13 and the nozzle 12 are held firmly in spaced relation to the end walls 22. While flange 16 rests on section 31a, it is protected as this section forms a cushion on tray bottom 21. The rest of the syringe is firmly held in spaced parallel relation to tray bottom 21 and to the upper edges of the tray side and end walls.

The insert is inexpensive, efficient, and easily used. The transversely extending trough formed by sections 31d, 31e and 31f allows the syringe to be readily grasped for insertion or removal.

While a specific embodiment of the invention has been shown and described in detail to illustrate the application of the invention principles thereto, it should be understood that the invention may be otherwise embodied without departing from such principles.

What is claimed is:

1. In combination with a syringe of the type having a barrel provided with a flange at its outer end and a plunger having a flange at its outer end and engaged within the barrel, a carton including a tray having a base and side and end walls, a filler insert for the tray including an elongated strip of relatively stiff material having a width equal to the inside width of the tray, said strip being folded about longitudinally spaced transverse lines to form first and second spaced panels substantially equal in length and interconnected by a first relatively short wall, said first panel lying against the tray base and engaging one tray end wall, said first short wall lying against said one tray end wall, a third panel engaging the tray base and connected to said second panel by a second relatively short wall substantially equal in length to the first short wall to support the second panel in spaced parallel relation to the tray base, and a fourth panel lying against the tray base and engaging the other tray end wall and interconnected to the third panel by a pair of substantially equal length upwardly extending panels; said second panel having a cut-out shaped to fit the outer ends of the barrel and plunger, including cut-out extensions snugly receiving the barrel and plunger flanges, the longitudinal spacing of the extensions being greater than the spacing of such flanges when the plunger is fully pushed into the barrel, and said second short wall having a cut-out to receive the barrel and continuous with the panel cut-out; said upwardly extending panels being formed with matched recesses extending from the upper edges of said upwardly extending panels to points spaced from the lower edges of the latter and engageably receiving the inner end of the barrel and supporting the same in spaced relation to the tray base; said first panel forming a reinforcing and cushioning layer engageable by the barrel flange.
2. In combination with a syringe of the type having a barrel provided with a flange at its outer end and a plunger having a flange at its outer end and engaged within the barrel, a carton including a tray having a base and side and end walls, a filler insert for the tray including an elongated strip of relatively stiff material having a width equal to the inside width of the tray, said strip being folded about longitudinally spaced transverse lines to form first and second spaced panels substantially equal in length and interconnected by a first relatively short wall,

5. having a barrel provided with a flange at its outer end and a plunger having a flange at its outer end and engaged within the barrel, a carton including a tray having a base and side and end walls, a filler insert for the tray including an elongated strip of relatively stiff material having a width equal to the inside width of the tray, said strip being folded about longitudinally spaced transverse lines to form first and second spaced panels substantially equal in length and interconnected by a first relatively short wall,

said first panel lying against the tray base and engaging one tray end wall, said first short wall lying against said one tray end wall, a third panel engaging the tray base and connected to said second panel by a second relatively short wall substantially equal in length to the first short wall to support the second panel in spaced parallel relation to the tray base, and a fourth panel lying against the tray base and engaging the other tray end wall and interconnected to the third panel by a pair of substantially equal length upwardly extending panels folded to form an inverted V; said second panel having a cut-out shaped to fit the outer ends of the barrel and plunger, including cut-out extensions snugly receiving the barrel and plunger flanges, the longitudinal spacing of the extensions being greater than the spacing of such flanges when the plunger is fully pushed into the barrel, and said second short wall having a cut-out to receive the barrel and continuous with the panel cut-out; said upwardly extending panels being formed with matching recesses extending from the upper

edges of said upwardly extending panels to points spaced from the lower edges of the latter and engageably receiving the inner end of the barrel and supporting the same in spaced relation to the tray base; said first panel forming a reinforcing and cushioning layer engageable by the barrel flange.
